United States Patent Office

Des. 175,723
Patented Oct. 4, 1955

175,723

TABLE LAMP

Harry B. Gross, Forest Hills, N. Y., assignor to Karbrite
Manufacturing Corporation, Brooklyn, N. Y., a corporation of New York

Application February 9, 1955, Serial No. 34,431

Term of patent 3½ years

(Cl. D48—20)

The single drawing figure is a side perspective view of a table lamp showing my new design.

The dominant features of my design are shown in solid lines.

I claim:

The ornamental design for a table lamp, substantially as shown and described.

No references cited.

UNITED STATES PATENT OFFICE
CERTIFICATE OF CORRECTION

Design No. 175,723

October 4, 1955

Harry B. Gross

It is hereby certified that error appears in the above numbered patent requiring correction and that the said Letters Patent should read as corrected below.

The name of the assignee was erroneously described and specified as "Karbrite Manufacturing Corporation" whereas said name should have been described and specified as -- Karlrite Manufacturing Corporation --.

Signed and sealed this 8th day of November 1955.
